CLAIM

The ornamental design for a multi-tool with bit slot, as shown and described.

DESCRIPTION

FIG. 1 is a top front perspective view of an embodiment of a multi-tool with bit slot showing a new design;
FIG. 2 is a top rear perspective view of the multi-tool as illustrated in FIG. 1;
FIG. 3 is a bottom rear perspective view of the multi-tool as illustrated in FIG. 1;
FIG. 4 is a top view of the multi-tool illustrated in FIG. 1;
FIG. 5 is a bottom view of the multi-tool illustrated in FIG. 1;
FIG. 6 is a front view of the multi-tool illustrated in FIG. 1;
FIG. 7 is a rear view of the multi-tool illustrated in FIG. 1;
FIG. 8 is a left side view of the multi-tool illustrated in FIG. 1; and,
FIG. 9 is a right side view of the multi-tool illustrated in FIG. 1.

The broken lines depict portions of the multi-tool with bit slot in which the design is embodied that are not considered part of the claimed design.

1 Claim, 5 Drawing Sheets
